(57) **CLAIM**

The ornamental design for a connector, as shown and described.

DESCRIPTION

FIG. 1 is a perspective view of a connector showing our new design;
FIG. 2 is a front elevational view of the connector;
FIG. 3 is a rear elevational view of the connector;
FIG. 4 is a left side elevational view of the connector;
FIG. 5 is a right side elevational view of the connector;
FIG. 6 is a top plan view of the connector; and,
FIG. 7 is a bottom plan view of the connector.

(Continued)

The broken lines in the drawings show portions of the connector that are only for environmental purposes and form no part of claimed design.

1 Claim, 7 Drawing Sheets
